UNITED STATES PATENT OFFICE.

FREDERICK SARGENT AND HERMAN C. HEATON, OF CHICAGO, ILLINOIS, ASSIGNEES
TO THE BABCOCK & WILCOX COMPANY, OF BAYONNE, NEW JERSEY, A CORPORA-
TION OF NEW JERSEY.

WATER-TUBE BOILER.

1,311,467.

Specification of Letters Patent. Patented July 29, 1919.

Application filed April 14, 1916. Serial No. 91,003.

To all whom it may concern:

Be it known that we, FREDERICK SARGENT and HERMAN C. HEATON, citizens of the United States, residing at Chicago, in the county of Cook and State of Illinois, have invented certain new and useful Improvements in Water-Tube Boilers, of which the following is a specification.

Our invention relates to water tube boilers and will be understood by reference to the following description, taken in connection with the accompanying drawings, in which Figure 1 is a central longitudinal section of one form of boiler embodying our invention, the drawing being more or less diagrammatic; Fig. 2 a side view, partly in section, of another form; Fig. 3 a section on the plane of the line 3—3 of Fig. 2; Fig. 4 a section on the plane of line 4—4 of Fig. 2; and Fig. 5 a vertical section on the plane of the line 5—5 of Fig. 1. Similar reference numerals indicate similar parts in the several views.

One of the objects of our invention is to so arrange the boiler heating surface that the area between the tubes for the flow of the gases from the furnace is decreased in a substantially uniform manner as the gases flow through the boiler, the area for the passage of the gases on entering the boiler tubes being considerably greater than that where they leave the boiler. Another object of the invention is to provide superheating surface and economizer surface, in addition to the boiler surface, and to so arrange the boiler, superheating and economizer surfaces that the hot gases will flow successively over the surfaces, and at the same time pass through areas which successively decrease from the front to the rear of the boiler.

In the boiler shown in Fig. 1 the numeral 1 designates the front wall, 2 the rear wall, and 3 the roof of the setting. The boiler is shown as fired with an underfeed stoker 4, although any other means for firing may be employed. The rear wall 2 is inclined from the bridge wall 5 so that the flow space for the gases, from the combustion chamber 6, between the side walls, the rear wall 2 and the roof 3, gradually decreases to the uptake 7.

Extending from side to side of the setting along the rear wall are a series of headers connected by banks of inclined tubes with

similar headers arranged immediately below the roof 3. The inclination of the rear wall 2 necessarily requires that the tubes connecting these two series of headers shall gradually decrease in length from the combustion chamber to the uptake. In the arrangement shown, the headers and tubes are connected in groups as follows:—The five headers 9 and 10 are connected by generating tubes 11; the three headers 12 and 13 are connected by superheater tubes 14; the seven headers 15 and 16 are connected by generating tubes 17; and the headers 18 and 19 are connected by economizer tubes 20. The hot gases from the furnace thus flow over the boiler tubes 11, then over superheater tubes 14, then over boiler tubes 17, and finally over the economizer tubes 20 to the uptake 7.

The feed water enters the economizer section of the boiler, preferably through the rearmost of the lower headers 18. If the lower economizer headers 18 are nipped together, and the upper headers 19 are similarly connected, then the water will be distributed through all the headers 18 and will flow upward through all of the economizer tubes to the upper headers 19. Instead of nipping the headers together, the flow of the water may be downward through the rearmost section of economizer tubes to the last lower header 19, thence upward through the next section of tubes, downward through the third section, and so on to the last section of tubes 20 to the header 19', which latter header is connected to two steam and water drums 21, one at each side of the boiler. Only one of said drums is indicated in Fig. 1. In this case the water is delivered through the inlet pipe 19² to the uppermost of the cross boxes 19.

If the flow of the water is up one section and down the next, so as to flow in series through each of the economizer sections, the counter-flow principle will be established and the entering or coldest water will be brought into contact with the coldest gases, the purpose being to more nearly equalize the temperature through the economizer to prevent sweating, that is, the deposition of moisture on the outside of the economizer tubes.

The two sets of headers 9 and 15, to which the lower ends of the generating tubes are connected, are nipped to two drums 22, one

at each side of the boiler as shown in Fig. 5. These drums are supplied with water from the steam and water drum 21 through the curved pipes 23, 24 and 25, extending 5 along each side of the boiler. The upper sets of headers 10 and 16 are connected to the steam and water drums 21. The steam generated in the tubes 11 and 17 passes from the headers 10 and 16 to the steam and water 10 drums, and thence through connections, one of which is shown at 26, into a cross-box 27 and headers 13 at the uppermost ends of the superheater tubes 14. The steam passes down through the superheater tubes 14 to 15 the headers 12 and is collected at each side of the boiler in boxes, one of which is shown in dotted lines at 28. From these boxes the steam passes to the steam mains.

At the front of the combustion chamber is 20 a bank of tubes 29 connected to lower and upper headers 30 and 31, respectively, these tubes preventing the front wall 1 from becoming overheated. They also form a 25 highly effective surface for the absorption of the radiant heat from the furnace and thereby add to the boiler capacity. The water for the tubes 29 is supplied from the headers 30 which are connected at each end 30 with drums 32. The latter are connected by the curved tubes 33 with the water spaces of the steam and water drums 21.

As shown in Fig. 1 some of the nippled 35 connections which lead from the ends of the horizontal headers are cross-sectioned and others are not so marked. Those connections which are cross-sectioned are connected directly into the steam and water drums, or the water drums, at the sides of the boiler, as 40 above described. Those connections of the economizer headers which are not sectional indicate either hand-hole fittings, which can be opened up for washing out the headers, or openings which may be used for attaching 45 drums or collector boxes at the side of the boiler. These drums or collector boxes if attached to the economizer would serve as a means for distributing the flow of water between the headers either in whole or in part.

In Figs. 2, 3 and 4 we have shown our 50 invention as applied to a boiler of the A-shaped type having a centrally disposed combustion chamber with firing openings at both the front and rear of the setting, and 55 with the boiler tubes, economizer and superheating banks of tubes, arranged on both sides of the combustion chamber. In Fig. 2 we have indicated both of the steam and water drums 21, and the connections from 60 said drums to the lower drums 22 to which the banks of generating tubes 11 and 17 are connected. The feed water enters through the pipe 34 to the economizer tubes 20 and flows therefrom through headers 19 to the 65 steam and water drums 21. From these lat-

ter drums the water is distributed through the curved tubes 23, 24 and 25 to the lower drums 22, and from the latter to the two banks of generating tubes. The steam from the steam and water drum flows through 70 the pipes 35 to a box 36, to which two of the rows of superheater tubes 12 are connected. The steam flows down these two rows of tubes to the lower box 37, and thence upward through the remaining rows of superheater tubes 12 to box 38, and thence to the steam main 39. The righthand side of the boiler will be arranged as is the left hand side.

In Fig. 3 we have indicated a connection 80 40 for the air blast for an induced draft system.

As shown in Figs. 1 and 2 each of the headers 9 is connected to its upper header 10 by a single row of tubes, while the remaining headers have connected to them two rows of tubes. The effect of this is to decrease the area between the tubes for the flow of the gases after they pass the generating tubes 11, and this, together with a reduction in area at successive banks of tubes, due to the inclination of the rear wall, results in less reduction in the velocity of the gases as their temperature decreases, than would occur with a gas passage of uniform 90 area. The wider spacing between the tubes which come nearest the fire is of advantage, in that it permits the mingling of the unburned combustible gases, and makes it possible to burn the combustible elements before the temperature of the gases is reduced below the point where combustion necessarily ceases. An additional advantage of the wider spaced tubes at the lower part of 95 the bank is that with a given capacity the heat transfer rate, due to the lower velocity of the gases, will be less than with narrower spaces, and the tubes will have a longer life.

Instead of decreasing the flow space for the gases by inclining one of the walls of the setting toward the other, and decreasing the lengths of the tubes, as above described, it is obvious that the flow space may be decreased in other ways, as by a closer spacing 110 of the tubes from the furnace to the uptake.

What we claim and desire to secure by Letters Patent of the United States is—

1. A water tube boiler having a bank of 120 substantially parallel tubes arranged in rows, the length of the tubes of a given row being the same and the lengths of the tubes of successive rows from the furnace toward the gas outlet decreasing, the tubes nearest 125 the furnace being generating tubes and said tubes succeeded by superheater tubes and economizer tubes, headers to which the ends of the tubes are connected, drums connected to the headers which in turn are connected 130

to steam generating tubes, said drums being also connected to certain of the economizer and superheater headers, a furnace discharging between the longer tubes, and a setting which, with the above arrangement of tubes, causes the gases to flow in one direction through decreasing flow areas.

2. A water tube boiler having a bank of substantially parallel tubes arranged in rows, the length of the tubes of a given row being the same and the lengths of the tubes of successive rows from the furnace toward the gas outlet decreasing, the tubes nearest the furnace being generating tubes and said tubes succeeded by superheater tubes, generating tubes and economizer tubes, headers to which the ends of the tubes are connected, drums connected to the headers which in turn are connected to steam generating tubes, said drums being also connected to certain of the economizer and superheater headers, a furnace discharging between the longer tubes, and a setting, which, with the above arrangement of tubes, causes the gases to flow in one direction through decreasing flow areas.

3. A water tube boiler having a bank of substantially parallel tubes arranged in rows, the length of the tubes of a given row being the same and the lengths of the tubes of successive rows from the furnace toward the gas outlet decreasing, the tubes nearest the furnace being generating tubes and said tubes succeeded by superheater tubes and economizer tubes, headers to which the generating tubes are connected, drums connected to said headers, upper and lower

headers to which the superheater tubes are connected, a cross box to which said upper headers are connected and pipes connecting the same with said drums, a steam outlet connection from said lower headers, a furnace discharging between the longer tubes, and a setting which, with the above arrangement of tubes, causes the gases to flow in one direction through decreasing flow areas.

4. A water tube boiler having a bank of substantially parallel tubes arranged in rows, the length of the tubes of a given row being the same and the lengths of the tubes of successive rows from the furnace toward the gas outlet decreasing, the tubes nearest the furnace being generating tubes and said tubes succeeded by superheater tubes and economizer tubes, headers to which the ends of the tubes are connected, drums connected to at least a part of said headers, a furnace discharging between the longer tubes, and a setting which, with the above arrangement of tubes, causes the gases to flow in one direction through decreasing flow areas, a bank of substantially vertical tubes in proximity to the front wall of the setting, and connections between said last-named bank of tubes and said drums.

In testimony whereof we have hereunto signed our names in the presence of two subscribing witnesses.
